UNITED STATES PATENT OFFICE.

HARRY W. HOADLEY, OF FINDLAY, OHIO.

RUG-CLEANING FRAME.

Application filed July 25, 1921. Serial No. 487,341.

To all whom it may concern:

Be it known that I, HARRY W. HOADLEY, a citizen of the United States, residing at Findlay, in the county of Hancock and State 5 of Ohio, have invented a new and useful Rug-Cleaning Frame, of which the following is a specification.

This invention relates to a frame for use in cleaning rugs, one of its objects being to 10 provide means whereby a rug can be stretched and held prior to the cleaning operation and can subsequently be stood up in a small space to dry.

Another object is to provide a frame 15 which can be adjusted readily to rugs of different sizes and which is capable of a further adjustment to stretch the rug after the same has been applied thereto, thus to hold the rug taut during the cleaning operation 20 and prevent it from shrinking and becoming distorted while drying.

Another object is to provide a rug holding device which will support the body portion 25 of the rug while said rug is being stretched.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings

Figure 1 is a plan view of one form of 40 rug holding structure.

Figure 2 is a section on line 2—2, Figure 1.

Figure 3 is a detail view of the stretching tool used in connection with the structure.

Figure 4 is a view partly in section and partly in elevation of the applying tool.

Figure 5 is a plan view of a modified structure.

Figure 6 is a section on line 6—6, Figure 5.

Referring to the figures by characters of reference 1 designates an end member and 2 a side member. These members are disposed in lapped relation as shown at 3 where 55 they are bolted together and secured to the top face of the side member 2 is a brace 4

which extends up to and is flush with the top of the member 1. Another brace member 5 is secured to the bottom of the end member 1 and extends up to the side member 2. Thus the braces 4 and 5 lap and can be fastened together as shown at 6. Consequently the side and end members will be held rigidly at right angles to each other.

A longitudinal slot 7 is formed in the free end portion of the side 2, the lower portion of the slot being enlarged as indicated by dotted lines at 8. Another longitudinal slot 9 is formed in the free end portion of the end member 1. Secured to the top face of the member 2 along the inner edge thereof is a longitudinal cleat 10 and a similar cleat 11 is secured along the bottom of the end member 1 at the outer edge thereof. Prongs 12 extend through the cleat 10 and additional prongs 13 extend through the end member 1, the free ends of the prongs 12 and 13 being supported in approximately the same plane. It is to be understood that the brace 4 and the cleat 10 are in the same plane with the top of the member 1 and that the bolts connecting the members 1 and 2 and the braces are all arranged in countersinks so that a smooth surface will be presented to the rug engaging the prongs.

The slotted end of the side member 2 extends under one end of an adjustable end member 14 through which extends a bolt 15 the head of which is seated in the enlarged portion 8 of the slot 7. This bolt is engaged by a nut 16 so that the members 2 and 14 can be held together securely. Prongs 17 are extended upwardly through the adjustable end strip 14 and a reenforcing cleat 18 is secured to the bottom face of the end member. An opening 19 is formed in that end of the member 14 adjacent the slot 7 and a longitudinal series of openings 20 is formed in the member 2.

The slotted end of the end member 1 extends over one end of an adjustable side member 21 and in this side member is mounted one end of a bolt 22 the other end of which extends through the slot 9 and is engaged by a nut 23. A longitudinal cleat 24 is secured on the member 21 and has prongs 25 extending therethrough and upwardly therefrom.

A longitudinal slot 26 is formed in the side member 21 adjacent one end where it is lapped by one end of the member 14, there being a longitudinal slot 27 in said end. The

lower portion of the slot 26 is enlarged as indicated by dotted lines at 28 and seated in this enlarged portion is the head 29 of a bolt 30 which extends through the slot 27 and is engaged by a nut 31. A block 32 is mounted to slide on the member 21 and is held adjustably thereto by a bolt 33 the head of which is seated in the enlarged portion 28 of the slot 26 while the upper end of the bolt is engaged by a nut 34.

An opening 35 is formed in the slotted end of the end member 14. A longitudinal series of openings 36 is formed in the end member 14 and another longitudinal series 15 of openings 37 is formed in the member 21.

The space surrounded by the members of the frame is adapted to receive a platform 38 suitably constructed and provided at one end with a removable extension strip 39 and 20 at one side with a removable extension strip 40.

In using this device the strips 39 and 40 are removed, the bolts 15, 22, 29 and 32 are loosened and the members 14 and 21 are 25 shifted toward the adjacent edges of the platform. The rug to be cleaned is then placed on the prongs 12, 13, 17 and 25, it being understood that the edges of the rug are drawn taut during this operation.

30 In applying the rug to the prongs a tool is used such as shown in Figure 4. This tool comprises a handle 41 having a short tube 42 projecting from one end thereof. The tube is placed against the rug directly over 35 a prong and is pressed downwardly so as to force the rug onto the prong. Thus the rug can be more readily applied than when forced onto the prongs with the bare hands. After the rug has been placed in position a 40 tool such as shown in Figure 3 is used for stretching the rug. This tool includes a lever 43 having a projecting stud 44 at one end and an arm 45 is pivotally connected to the lever and has a projecting stud 46. The stud 44 is placed in the opening 19 and the stud 46 is inserted into one of the openings 20. By then swinging the lever the member 14 will be shifted longitudinally along the member 2 after which the bolt 15 can be 50 tightened. Stud 44 is then inserted into an opening 47 in the side member 21 while stud 46 is inserted into one of a series of openings 48 in the member 1. Thus member 21 can be shifted longitudinally of the member 1 and then held by tightening the bolt 22.

55 Stud 44 is then inserted into the opening 35 and the stud 46 into one of the openings 37 after which the member 14 is shifted longitudinally along the member 21. Block 32 60 is adjusted against the member 14 and secured by tightening the bolt 33. Thereafter the stud 46 is inserted into one of the openings 36 so that the member 21 can be shifted longitudinally along the member 14 after 65 placing stud 44 in an opening 37. The two

members can then be held by tightening the bolt 30. Thus the rug will be stretched tightly and the extension members 39 and 40 can be inserted so as to practically close the spaces between the platform and the adjacent members of the frame. This platform will support the central portion of the rug. The rug can now be thoroughly washed or otherwise cleaned after which the frame can be placed in an upright position with the rug remaining attached thereto. Thus the rug will be held taut and in proper shape until it has dried.

Where small rugs are to be cleaned several of them can be mounted in a single 30 frame of the modified construction shown in Figure 5. This frame includes a side member 49 to which are fixedly secured end members 50. Another side member 51 is detachably secured to the end members 50 35 by means of bolts 52. These bolts can be inserted into different openings 53 so as to hold the side member 51 at a desired distance from the member 49. Extending through the member 51 are bolts 54 which 40 engage longitudinally slotted strips 55. To one end of each of these strips is attached a cross strip 56. Extending through each of the cross strips 56 is a holding member 57 of stiff wire or the like terminating in 45 an upstanding prong 58 lapping the inner side of the member 56. A similar arrangement of prongs 59 is provided along the inner side of the member 49. Rugs can be secured at their ends to the prongs 59 and 50 arranged side by side, the other ends of the rugs being attached to the prongs on the respective strips 56. The said strips 56 are then drawn towards the side member 51 55 after which the bolts 54 are tightened. Thus the rugs will be held taut within the frame and will rest upon the table or other flat surface T on which the frame is supported. Thus the rugs can be cleaned and afterwards the frame can be placed in an upright 60 position to support the rugs until dry.

What is claimed is:—

1. A device of the class described including a frame, means thereon for engaging the edge portions of a rug, thereby to hold the edge portions of the engaged rug in a common plane, and an expandible platform removably supported within the frame and having a flat rug supporting surface in the same plane with the rug engaging means 115 for supporting the greater portion of the rug in the same plane with the edge portions thereof.

2. A device of the class described including rigidly connected frame members, members adjustably connected to each other and to the respective rigidly connected members, said adjustable members being disposed in lapped relation to each other and to the fixed members, clamping bolts extending 120 125 130

through the lapping portions of the members, an adjustable abutment locked upon one of the adjustable members and movable against the other adjustable member, and means extending through the lapping portions of the members for holding them against relative movement.

In testimony that I claim the foregoing as my own, I have hereto affixed my signature in the presence of two witnesses.

HARRY W. HOADLEY.
